3 SHEETS—SHEET 3.

UNITED STATES PATENT OFFICE.

EDWARD FRIEDRICH, OF SAN ANTONIO, TEXAS.

BUTCHER'S ICE BOX.

1,420,088.

Specification of Letters Patent. Patented June 20, 1922.

Application filed May 28, 1921. Serial No. 473,425.

To all whom it may concern:

Be it known that I, EDWARD FRIEDRICH, a citizen of the United States, residing at San Antonio, in the county of Bexar and 5 State of Texas, have invented a new and Improved Butcher's Ice Box, of which the following is a specification.

This invention generically comprehends a new and effective method of refrigeration, 10 in which the parts are more especially designed for directing the circulation of air in a practically dry state to ensure the maintenance of uniform temperature within the container or goods holding compartment and in which the said parts are especially well adapted for use in connection with butchers' ice boxes, counter display refrigerators or refrigerator cars.

Another object of my invention is to provide 20 a salt brine refrigerating means for butchers' ice boxes, display counter refrigerators and the like, in which the cooled air is adapted for being constantly maintained in circulation within the goods container compartment, in a substantially dry state, and the air, as the temperature thereof is raised, owing to its contact with the material within the refrigerating chamber, is caused to pass back to the ice chest for 25 re-cooling and so circulated that a much lower refrigerating temperature, with less consumption of ice, is had than is possible in the regular forms of butcher and counter display refrigerators now in general use.

In its more complete nature, my invention embodies in a refrigerator of the general type stated, certain features of construction and combination of parts especially designed for a more economical use of ice for cooling 30 the goods within the holding compartment or chamber of the refrigerator and for establishing a constant circulation of the cold air through the ice container and the goods compartment for repeatedly reusing 35 the same air without fresh air from the outside of the refrigerator other than that which naturally finds its way into the refrigerator.

With other minor objects in view, all of 40 which will hereinafter be fully stated, my invention consists of an improved construction of butcher's ice box or refrigerator that embodies the novel features of construction and detailed arrangement of parts

fully set out in the following description 55 thereof, specifically mentioned in the appended claims and illustrated in the accompanying drawings, which show a preferred development of my invention, the details of which may be varied or modified to suit the 60 special application of my invention in connection with the different types of butchers' ice boxes, counter refrigerators, refrigerator cars, etc., without going beyond the scope of the claims. 65

In the drawings:

Figure 1 is a perspective view of a butcher's refrigerator embodying my invention, parts of the refrigerator walls being broken away to the better illustrate the 70 ice box construction that constitutes the essential feature of this invention.

Figure 2 is a longitudinal section of the refrigerator, the air circulation being indicated by arrows. 75

Figure 3 is a horizontal section taken on the line 3—3 of Figure 2.

Figure 4 is an inverted perspective view of the bottom of the ice container and the air cooling chest. 80

Figure 5 is a detail perspective view, parts being in section, of the water draining base that cooperates with the ice container and the air cooling chest, the same being shown in its operative position on the 85 drain platform located at one end of the refrigerator housing.

Figure 6 is an inverted detail perspective view of one of the individual drain trough units. 90

Figure 7 is a detail section that illustrates the cooperative relation of the perforated bottoms of the ice holding compartments and the brine drip retaining troughs, hereinafter explained. 95

In the drawings I have shown my invention as embodied in connection with a butcher's ice box or counter display refrigerator, the same being shown as an elongated body composed of the usual panelled opposite sides 1—1 and opposite ends 2—2, a bottom 3 and a top 41, the construction of the walls of the said body, in practice, having the usual insulation features, whereby to retain as much cold air as possible inside of the refrigerator, it being understood that the refrigerator body or housing construction constitutes, per se, no part of my 100
105

invention, which is confined to the peculiar construction and arrangement of the ice chest and the air cooling means hereinafter specifically stated and best illustrated in Figures 2, 3 and 4 of the drawings.

At one end the housing has a doorway 5 and near that end opposite the doorway the housing top has a hinged lid 6 that covers an opening 60 in the top for gaining access 10 to the ice chest, as will presently further appear.

7—7 designate hanger racks located along the opposite sides of the goods containing compartment α of the refrigerator, as is 15 clearly shown in Figure 2 of the drawings, by reference to which it will also be observed, at that end opposite the doorway of the housing, is located the ice chest and air cooling means, the special construction of 20 which forms the essential feature of this invention, as before stated.

The combined ice chest and air cooler 8 which, in practice, is made up of heavy sheet metal, includes opposite end walls 80, 25 a back wall 81, and an open top 82 through which the ice is placed into the chest and which is normally closed by a removable cover 83 adapted for being readily lifted out through the lid covered opening 60 in 30 the housing top when the lid 6 is thrown back.

The ice chest, the construction of which is best shown in Figures 2, 3 and 4, is composed of a substantially rectangular shaped 35 sheet metal body that includes a series of alternately positioned air chambers 4 and ice containers 9, and the said chambers 4 and containers 9 extend vertically the full height of the chest body, as is clearly shown in Figure 2.

The aforesaid alternately positioned air chambers 4 and ice containers 9 are substantially wedge shaped in horizontal section and the said air chambers and ice containers are 45 further alternately disposed by reason of the larger ends of the air chambers 4, which open through the inner wall of the chest body, being located adjacent the smaller closed ends of the ice containers 9 whose 50 larger ends are closed by the back wall 81 and are disposed between the smaller ends of the air chambers 4, as will be readily understood by reference to Figure 3.

Referring now more particularly to Figure 4 of the drawings it will be observed the substantially wedge shaped air spaces or chambers 4, whose smaller ends terminate at the back wall 81 of the chest 8, alternate with a like-shaped set 60 of vertically disposed ice compartments 9 which extend the full height of the said chest 8, the said ice holding compartments having their larger ends adjacent the back wall 81 and next the smaller ends of the 65 air compartments and the smaller ends of

the said ice container compartments are closed as at 90 and located between the larger ends of the said air cooling compartments 4.

The several sets of alternately arranged air cooling compartments and ice holding 70 chambers may be formed in any suitable way, but on account of economy of structure and rigidity of the parts, I prefer to form each air chamber of a single sheet of galvanized iron that is bent into a substantially 75 wedge shaped in horizontal section, whose smaller end is soldered, or otherwise rigidly, secured to the pendent front member 10 of the housing 8.

The spread ends of each metal sheet of 80 which the ice compartments are formed are turned in at right angles to form flanges 11 and these flanges are soldered, or otherwise made fast, to the back wall 81 and the top of the spaces between each adjacent pair of 85 substantially wedge shaped ice holding compartments is closed by a like member 14, the several members 14 constituting the top for the air compartments 4 located between each pair of ice compartments and which 90 open through the front wall of the combined ice holding and air cooling chest, as shown.

The air receiving and cooling spaces are each divided into a tier of vertically aligned 95 air spaces, by the horizontal division plates 15, which are so shaped that they extend back the full length of the said air spaces, from the open front end of the chest to the back wall 81 thereof, and the said wall constitutes the back end of all of the tiers of air cooling spaces. The back wall 81, as is clearly shown in Figure 2, has a series of air passages 85 which, in the practical development of my invention are preferably 14 105 inches in diameter.

The divisions 15, before referred to, incline downwardly from the back wall to the front open end of the chest for reasons presently explained.

The lowermost tier of air spaces or compartments and the ice compartments are closed by a series of plates 16 which are bounded at their opposite sides by pendent vertical flange projections 16^a whereby to provide a series 115 of alternately and inwardly directed fan shaped grooves 17 along the bottom of the chest 8, the alternate ones of the bottom members 16 that constitute the closures for the ice chamber each having a series of apertures 18 through which the drippings from the ice compartment drop.

The back ends of the grooves on the under side of the chest 8 are closed by the bottom edge of the back wall 81, as shown, and at 125 the opposite ends the bottom of the chest has bifurcated members 20—20 which are provided for interlockably engaging stout pipe supports 21—21 for sustaining the bottom of the chest above a supplemental bottom, the 130

construction of which is best shown in Figure 5, and whose purpose will be hereinafter stated. In the practical use of my construction of refrigerator so far as described, the 5 ice chest is filled with crushed ice and salt, and in a refrigerator proportioned along the lines shown in the drawings, 8 pounds of salt are required for each 100 pounds of ice, the latter being supplied in a crushed condition 10 through the opening 60 in the top 41 of the housing and into the open top of the chest 8 the ice holding compartments are filled and the tops thereof and the tops of the air spaces or compartments are covered 15 with ice.

The supplemental bottom before referred to consists of a stout pipe frame which includes a series of standards 25 that connect at their upper ends with a rectangular shaped 20 horizontal frame portion, the end supports 21—21 of which constitute the supports engaged by the bifurcated members 20 on the bottom of the chest 8, as before mentioned.

25 The several standards 25 also serve as supports for transverse front and back rods 26—27, the purpose of which will be best understood, by reference to Figures 5 and 6, which show sheet metal bottom members 30 32—32 on the top of which are secured fan shaped troughs 33 which are separated by like air shaped passages 34—34, the troughs 33 and the air passages 34 alternating, the troughs 33 being adapted for cooperating 35 with the apertured bottoms of the ice compartments and into which the drippings from the said compartments gather and overflow at 35 into a transversely disposed trough 36 common to all of the troughs 33 40 and which is formed in the inner end of a platform 37 upon which the supplemental bottom is supported when the parts are assembled for use, as clearly shown in Figure 2.

45 The sheet metal bottom members 32 incline downwardly from the back to the front end to cause the drippings to pass out over the front ends of the trough 33 into the trough 36, before referred to, and which discharges 50 through an offtake pipe 38 that passes to the outside of the housing, as shown.

From the foregoing description taken in connection with the drawings, the complete 55 construction, the manner of use and the advantages of my improved form of refrigerator will be readily apparent to those familiar with the use and the manufacture of refrigerators of the general type shown and 60 described.

By reason of alternately arranging the air and ice chambers 4 and 9 in the manner described and best shown in Figure 3, that is, with the smaller or contracted ends of the 65 air chambers 4 adjacent the larger ends of

the ice chambers 9, the air that enters the chambers 4, through the apertures 85 in the back wall 81, at the smaller ends of the said chambers 4, spreads as it passes to the front end of the said chambers 4 and is thus subjected to constantly cooling action as it circulates over and between the adjacent 70 iced walls of the pairs of opposite ice compartments 9, it being understood the warm air within the goods holding compartment of 75 the refrigerator is constantly kept in motion and drawn back over the ice chest (see arrows on Figure 2) down back of the wall 81 and constantly returns through the ice chest into the compartment X, the said air being 80 recooled as it passes through the spaces 4—4, the arrangement of the parts stated tending to effect a continuous circulation and re-cooling of the air and in such manner that a practical refrigeration of the articles within 85 the goods holding compartment X is provided for.

Furthermore, after the air passes into the storage space (that is, the compartment in which the perishables are kept) there must 90 be a system to again bring the cold air, which eventually gets warmer, back through the ice tank chambers for re-cooling. As, naturally, the warm air rises toward the ceiling of the housing, the storage compartment 95 is equipped with a supplemental or blind top 40 which extends horizontally from the top of the chest 8 to near the doorway end of the housing. This blind top 40 provides a return warmed air route for the air within 100 the storage compartment and thereby causes the warmed air to take the course indicated by the arrows on Figure 2 from the storage chamber over and around the back and side walls of the chest 8 and to return directly 105 through the air passages 85 in the back wall 81 of the chest, through the cold air spaces 4, the downwardly inclined horizontal partition causing the air, that returns through the apertures 85 at the back or contracted 110 ends of the air chambers 4, to pass through separate horizontal ducts to the compartment X, as indicated by the arrows on Figure 2, by reference to which it will be noticed that such of the return air that may 115 pass down to the bottom of the back of the chest 8 returns through the supplemental air channels 34—34 at the bottom back into the storage chamber thereby creating a continuous circulation through the interior of 120 the refrigerator.

It should be mentioned that in my construction of refrigerator only cracked ice mixed with 8 per cent of salt is placed in the ice spaces of the ice chest and air cooling 125 casing and the brine as it collects in the said ice spaces drips through the perforations in the bottoms of the said ice holders or spaces.

The perforations in the bottoms of the 130

ice and salt holding spaces cause the mixture of ice and salt, as the same melts into the form of brine, to immediately leak out into the gutters 33, located thereunder and in which the brine is retained until the gutters gradually fill; after which, they continuously overflow into the offtake trough 36.

Collecting the brine drippings from the ice containers 9—9 and passing the same under the ice chest through the channels 34, as stated and shown, aids in maintaining the air circulation as the said air passes from the back end of the ice chest under the ice chest and returns to the refrigerating compartment. It is a proven fact that ice simply laying flatwise on a platform in an ice box will not produce cold dry air. By my system, as before explained and shown in the drawings, the warmer up draft air and the colder down draft air carried through the refrigerator, as hereinbefore explained, produces a cold dry air, instead of a saturated or wet air, as is usual in refrigerator systems in which the air is passed directly over the ice.

In my construction of refrigerator sufficient fresh air supply is maintained by air sucked in through the cracks around the top cover 6, which latter fits the opening 60 loosely.

What I claim is:

1. In a butcher's ice box of the character stated, a combined ice holding and air cooling chest having a series of alternately disposed vertical spaces, one set of the said spaces forming air chambers, one end of each of which chambers is open the full height thereof, the other end of which has a series of air passages whereby to provide for the free circulation of the air, in horizontal direction, through the said air chambers, the other set of chambers extending substantially the full height of the chest and open at the top of the chest for the reception of ice, the said ice and air chambers being substantially wedge shaped in horizontal section and alternately disposed, relatively to each other, whereby the wide ends of the air chambers are disposed between the narrow ends of adjacent pairs of ice chambers and the wider ends of the ice holders are likewise located between the narrow ends of adjacent pairs of air chambers, the bottom of the ice holders having apertures, a platform on which the chest rests, supports for holding the bottom of the chest above the platform, and alternately disposed sets of troughs and air spaces located on the platform under the air and ice chambers of the chest, the said troughs and air spaces being substantially wedge shaped in horizontal planes.

2. In a refrigerator, a combined ice and air cooling chest consisting of a series of alternately disposed vertical chambers, one

set of the said chambers forming air spaces that are in open communication with the storage compartment and the other set of chambers being open through the top of the chest and constituting the ice and salt receptacles, the storage compartment having provision for delivering the ice and salt into the said ice chambers, the said ice and air chambers being substantially wedge shaped in horizontal section, the air chambers being disposed with their wide ends in communication with the storage compartment, the ice chambers having their wide ends disposed between the narrow or innermost ends of the said ice chambers and their narrow and closed ends located between the wide ends of the air chambers, the said several vertically disposed air chambers being each divided by a series of horizontal division members that incline from the inner or rear ends of the said air chambers to the front end of said chambers, the bottom of the ice chambers having drip apertures through which the brine that accumulates in the said ice chambers escapes, and means for collecting the brine that passes from the gutters and discharging the same externally of the refrigerator.

3. In a refrigerator, a combined ice and air cooling chest consisting of a series of alternately disposed vertical chambers, one set of the said chambers forming air passages that are in constant open communication with the storage compartment and the other set of chambers being open through the top of the chest and constituting provision for delivering the ice and salt into the said ice chambers, the said ice chambers and air passages being substantially wedge shape in horizontal section, the air chambers being disposed with their ends in communication with the storage compartment, the ice chambers having their wide ends disposed between the narrow or innermost ends of the said ice chambers and their narrow and closed ends located between the wide ends of the air chambers, said ice chambers having brine outlets in their bottoms, a supplemental bottom on which the chest is supported having alternately disposed substantially wedge shape passages and like shaped troughs, the troughs being adapted to receive the drippings from the ice chambers and the passages serving as air ducts through which portions of the recooled air passes into the storage compartment, and a platform upon which the supplemental bottom rests, the said platform having a transverse trough into which all of the drip collecting troughs overflow, and an offtake from the said trough through the wall of the refrigerator housing.

4. In a refrigerator of the character described, a housing having a storage compartment provided with a doorway at one

- end, a combined ice holding and air cooling chest adjacent the other end of the said compartment, the top of the said chest being disposed below the top of the housing, the latter having a door closed opening above the chest, a supplemental inside top projected forwardly from the top of the chest to near the door end of the storage compartment whereby to provide a warm air passage under the ceiling of the housing and above and beyond the chest, the said chest having alternately disposed ice and air spaces extending the full height thereof, the air spaces being closed at the top, bottom, the sides, and having the inner ends open the full height to the storage compartment, the ice spaces being open at the top for the reception of the ice and salt and supported above the bottom of the storage compartment, the bottom of the ice spaces having drip outlets that also constitute brine passages, all being arranged substantially as shown, whereby the warm air as it accumulates within the storage compartment and naturally rises to the ceiling is drawn off over the supplemental top, over the top and back and under the chest back in a re-cooled condition into the storage compartment.
5. In a refrigerator of the character stated, a combined ice holder and air cooler comprising a sheet metal body including opposite sides and a back wall that merges with the said sides, a series of partitions each formed of a sheet metal member bent upon itself into a substantially wedge shape in horizontal section, the ends of the opposing bent portions of the partitions being fixedly attached to the back wall of the metal body and extended from the lower edge to near the top edge of the opposite sides of the aforesaid body whereby to provide alternate substantially wedge shaped vertical ice receivers and intervening vertically extended air spaces, the latter opening through the front of the combined ice holder and air cooling body, the back wall of the said body having passages that open into the aforesaid vertical air spaces, horizontal partitions in the said air spaces that divide such spaces into a series of horizontal ducts, the lowermost one of said partitions constituting a closed bottom for the air spaces, perforated partitions that constitute the bottoms for the air spaces, the latter opening through the front of the combined ice holder and air cooling body, the back wall of the said body having passages that open into the aforesaid vertical air spaces, horizontal partitions in the said air spaces that divide such spaces into a series of horizontal ducts, the lowermost one of said partitions constituting a closed bottom for the air spaces, perforated partitions that constitute the bottoms for the air spaces, the lower edges of the bent portions extending below the bottom horizontal partitions of the ice holding and air spaces to thereby provide channels or passages under the said ice holding and cooling spaces.
7. In a refrigerator of the character stated, a combined ice holder and air cooler comprising a sheet metal body including opposite sides and a back wall that merges with the said sides, a series of partitions each formed of a sheet metal member bent upon itself into a substantially wedge shape in horizontal section, the ends of the opposing bent portions of the partitions being fixedly attached to the back wall of the metal body and extended from the lower edge to near the top edge of the opposite sides of the aforesaid body whereby to provide alternate substantially wedge shaped vertical ice receivers and intervening vertically extending air spaces, the latter opening through the front of the combined ice holder and air cooling body, the back wall of the said body having passages that open into the aforesaid vertical air spaces, horizontal partitions in the said air spaces that divide such spaces into a series of horizontal ducts, the lowermost one of said partitions constituting a closed bottom for the air spaces, perforated partitions that constitute the bottoms for the air spaces, the lower edges of the bent portions extending below the bottom horizontal partitions of the ice holding and air spaces to thereby provide channels or passages under the said ice holding and cooling spaces, a platform having alternately disposed air passages and fluid troughs, the body having the air and ice holding spaces having means at the lower edge for sustaining the said body with the air passages on the bottom in register with the air passages and fluid troughs on the platform.
8. In a refrigerator of the character stated, a combined ice chest and air cooler located within the said compartment near one end thereof, a supplemental ceiling for the storage chamber that extends from the top of the combined ice chest and air cooler to near the end of the storage compartment

opposite the ice chest end thereof, the said ice chest and air cooler having a closed top, bottom and opposite side walls and a back wall, alternately disposed vertical ice spaces 5 and air cooling spaces, the ice spaces being open at the top, horizontal partitions that divide each of the air spaces into a series of

horizontal tiers of chambers, the back wall of the ice chest cooler having passages that open into the air spaces for the return of the 10 warm air through the horizontal ducts of the air chambers into the storage compartment.

EDWARD FRIEDRICH.
